(57) **CLAIM**

The ornamental design for a camera, as shown and described.

DESCRIPTION

FIG. 1 is a front view of a camera showing our new design;
FIG. 2 is a top view thereof;
FIG. 3 is a rear view thereof;
FIG. 4 is a bottom view thereof;
FIG. 5 is a right side view thereof;
FIG. 6 is a left side view thereof;
FIG. 7 is a top, front perspective view thereof;
FIG. 8 is a top, rear perspective view thereof;
FIG. 9 is a bottom, front perspective view thereof; and,
FIG. 10 is a bottom, rear perspective view thereof.
The broken lines depict portions of a camera in which the
design is embodied and form no part of the claimed design.
